ELECTROMETER VACUUM TUBE

Auguste Louis Marie Antoine Rouy, New York,
N. Y., assignor to L. L. H. Company, Erie, Pa.,
a partnership comprising Hugh C. Lord,
Thomas Lord and Blanche M. Hartman

Application September 6, 1944, Serial No. 552,892

5 Claims. (Cl. 250—27.5)

1

My invention relates broadly to electrometer vacuum tubes and more particularly to an improved construction of electrometer vacuum tube for facilitating mass production of such tubes and obtaining a high degree of efficiency in operation.

One of the objects of my invention is to provide a construction of electrometer vacuum tube in which the electrodes are arranged for decreasing the ratio of grid current to plate current; effecting an increase in plate current; increasing the ratio of plate current to grid voltage; and decreasing the positive ion current.

Another object of my invention is to provide an arrangement for mechanically mounting the electrodes of an electrometer vacuum tube by which the mechanical rigidity of the different electrodes is insured.

Still another object of my invention is to provide a special arrangement of filament electrodes for electrometer vacuum tubes by which compensation for relative displacement of the filaments with respect to the other electrodes of the tube is obtained.

Still another object of my invention is to combine a construction of electrometer vacuum tube in which multi-point supports are provided for the tube electrodes and so related as to permit simultaneous uniform displacement of the electrodes relative to each other under conditions of mechanical vibration for minimizing changes in operating characteristics of the tube over such periods of vibration.

Other and further objects of my invention reside in the mechanical arrangement for mounting the filament grid and plate electrodes of electrometer vacuum tubes as set forth more fully in the specification hereinafter following by reference to the accompanying drawings in which:

Figure 1 is a theoretical plan view showing the relative arrangement of the filaments, plate and grid in the electrometer vacuum tube of my invention; Fig. 2 is a plan view of an arrangement of grid filament and plate electrodes used in prior art types of electrometer vacuum tubes over which the instant invention is a very substantial improvement; Fig. 3 is a curve diagram showing the characteristics of the electric fields plotted with respect to the function of the instantaneous position of an electron between the grid and plate electrodes comparing two structures of Figs. 1 and 2; Fig. 4 is a curve diagram illustrating the advantages obtained in the tube construction of my invention where greater field strength is secured in a position which increases efficiency in the tube operation; Fig. 5 is a schematic plan view showing the arrangement of filament electrodes in the tube construction of my invention by which uniform operation of the electrometer

2

vacuum tube is maintained independently of mechanical vibration; Fig. 6 is a vertical sectional view through an electrometer vacuum tube constructed in accordance with my invention with the plate electrode broken away and illustrated partially in section to more clearly show the arrangement of filaments and grid electrodes; Fig. 7 is a transverse section taken on lines 7—7 of Fig. 6; Fig. 8 is a transverse section taken on lines 8—8 of Fig. 6; Fig. 9 is a perspective view illustrating the upper support for the filament electrodes; and Fig. 10 is a perspective view illustrating the manner of supporting the plate electrode of the electrometer vacuum tube.

15 When it is necessary to measure very small currents or rather voltages in circuit where the total amount of energy is extremely low, like for instance in the case of voltages produced by pressure on a piezo electric quartz crystal cell, it is 20 of the utmost importance to avoid any losses of the minute electric charge through leakages in the voltage measuring devices.

Several types of vacuum tubes have heretofore been proposed in which the grid current is 25 kept as low as 10×10^{-14} amperes. These tubes are generally characterized by a very low plate current of the order of 200×10^6 microamperes in order to reduce the grid current. Some of them use a grid made with a plate on the opposite side 30 of the filament arranged for accelerating the electrons toward the plate in function of its negative potential. Some others are made with the grid surrounding the plate which is made in that case out of a mesh grid and then this grid 35 has a decelerating function on the electrons in function of its negative potential.

In either case the mechanical construction is such that the operation of these vacuum tubes is affected by even the smallest mechanical vibrations 40 producing some variations of the mechanical distances between the different electrodes therefore causing the plate current to vary with these minute relative displacements.

45 My improved construction of electrometer vacuum tube includes a number of advantages summarized as follows:

- a. Decrease of the ratio of grid current to plate current;
- b. Increase of the plate current;
- c. Increase of the ratio of plate current to grid voltage;
- d. Decrease of the positive ion current;
- e. Increase of the mechanical rigidity of the several electrodes;
- f. Special arrangement of the filaments compensating their relative displacement in respect to the coacting electrodes.

Referring to the drawings I have shown a cross section of the electrometer vacuum tube in Fig. 60 1 in which P represents the plate, F₁, F₂, F₃ rep-

resent the filaments and G represents the grid. The plate P and the grid G are concentric and the filaments F₁, F₂, F₃ are located on a concentric circle with P and G, at angular distances of 120° or 60°.

Fig. 2 shows the customary arrangement of the prior art types of electrometer tubes with grid G' and plate P' constituted by two plates extending parallel to each other.

In order to clearly distinguish the difference between my improved construction and the prior arrangement, the distance between grid and plate electrodes has been indicated the same in both instances.

In Fig. 1 it will be understood that any electron emitted by the filament F₁, for instance, will be obliged to hit the plate P or the grid G if its initial velocity is high enough. The electrons cannot escape outside of the space limited by the plate P and the grid G. However, in the arrangement of the prior art in Fig. 2 it will be seen that any electron following a path 3' will escape the attraction of the plate P' and may hit the glass bulb or envelope of the tube which in turn will become negative and disturb the functioning of the tube.

The structure of the tube of my invention is such that no electron emitted by the filament can escape hitting the plate. Thus the structure of my invention produces a decrease of the ratio of grid current to plate current.

This ratio is further decreased by the fact that the surface of the grid seen from the filament is far smaller in the case of Fig. 1 than in Fig. 2. In Fig. 1 the half dihedral angle α'' is approximately 10°, whereas in Fig. 2 this half dihedral angle is approximately 70° as shown at α'. The angle is bounded by the surface of grid G or G' and extends between theoretical angularly disposed planes from the filament as a boundary edge. The amount of electrons discharged at the same velocity and able to hit the grid is proportional to the dihedral angle. In accordance with my invention the ratio of grid current to plate current will be only

$$\frac{10}{70} = \frac{1}{7}$$

of the case of Fig. 2. This serves to distinguish the structure of my invention as depicted in Fig. 1 from the prior art as shown in Fig. 2.

Further study of the field strength in these two different cases will show the advantages of my construction. In the case of plane electrodes parallel to each other the value of the electric field strength is given by

$$F_p = \frac{E_b}{X_1 - X_0} \text{ volt/cm.}$$

In this equation E_b represents instantaneous field strength in volts at a selected reference position and X₁ - X₀ represents the increment of distance over which the measurement is taken. This field is constant in intensity all along the paths from the grid to the plate. In order to compute the field strength between two coaxial cylinders (grid and plate), the following equation is used:

$$F_m = \frac{E_b}{L_{rk}^{ra}} \times \frac{1}{r} \text{ volt/cm.}$$

which gives the field strength for any point p at a distance r from the axis of the cylinders; r_a and r_k being the radii of the plate and of the grid. The comparison between the two cases will be easily understood by using instead of the value

of the field strength for any given point, the value of the mean average value of this field when the electron is going from r₀ to r₁. The mean average value is then given by

$$F_m = \frac{E_b}{L_{rk}^{ra}} \times \frac{\frac{L_{r_1}^{r_1}}{r_1 - r_0}}{r_1 - r_0} \text{ volt/cm.}$$

10 Consider an example in which (for Fig. 1), the radius of the grid r_k = .15 cm., the radius of the plate r_a = .75 cm., distance between grid and plate in the two cases is d = .6 cm.

Fig. 3 shows the value of the different fields plotted in function of the position p of the electron between grid and plate for the two cases, that is the arrangement of Figs. 1 and 2.

For the plane electrodes, Fig. 2, the field is constant and its value is F_p = E × 1.666 volt/cm.

For the cylindrical electrodes, Fig. 1, the field decreases from F_c = E × 4.14 to F_m = E × .827 passing at F_c = E × 1.38 at midway between the electrodes. And in the same time the mean value of the field strength varies from F_m = E × 4.14 to the minimum value of F_m = F_p = E × 1.666. This fact is very important which leads to a substantial improvement in the reduction of the ratio of the grid current to the plate current.

Assuming, for example, that one electron is 30 coming toward the grid in either case with a velocity such that it can overcome the repulsion produced by the field strength of value

$$E_p = E \times 1.666$$

35 given by the plate grid and reaches it with a velocity equal to 0; the same electron with the same energy traveling toward the grid in case Fig. 1 will be stopped before reaching the grid and accelerated backward toward the plate because the field strength is greater than in the first case, the ratio being (Rho)

$$\rho = \frac{4.14}{1.666} = 2.484$$

45 and the energy of the same electron will not be enough to drive it to the grid.

The greater field strength in the neighborhood of the plate has the result to push back toward a positive grid the beginning of the grid electronic current; at the same time the slope of the curve of the grid current will make a smaller angle with the abscissa as a consequence of the reduction of the surface of the grid.

The curves in Fig. 4 show the result very clearly.

55 If the origin of grid current starts in M₂ for plate electrodes at a voltage V_g = -1.75 volts, for the same electron condition the grid current will start only at M₁ where the grid voltage is only V_g = -1.28 volts. The angle α₁ of the tangent in M₁ to the grid current curve is greatly reduced in comparison with the former type. Values of grid bias volts are indicated by the abscissa as -Z.

65 I locate several filaments F₁, F₂ and F₃, etc., intermediate the grid and plate and this serves to improve the electrometer tube operation by decreasing the ratio of grid current to plate current and increasing the plate current by the same amount when the filaments are maintained at 70 constant temperature. The radius of projection of the electrons is in the direction F₁O₁; F₂O₂; and F₃O₃. I further improve the characteristics of the tube by increasing the electric field strength in the region of the grid which is far more important than such a field in the region of the

plate electrode. By increasing the filament temperature, the density of emitted electrons is increased in the arrangement of my invention. It is possible to produce per filament an electronic plate current averaging 600 microamperes, the total output being 1.8 milliampere for a three filament set up giving a voltage amplification factor of about 2.25 volts per volt against .6 for prior types of electrometers. By using a six filament set up these last values are nearly doubled.

The next advantage obtained by the type of electrometer tube of my invention is the decrease of the positive ion currents. This result is obtained by using for the plate and the grid a material like tantalum which while being heated up during the vacuum build up is freed of all included gases and which provides a gas free tube during normal operation as a consequence of the tremendous absorption of gases by the tantalum.

In certain cases the heat treatment of the tantalum affords a large reduction of the secondary emission which is always of a deleterious nature in the vacuum tubes especially in this case.

One of the main sources of disturbances created by the mechanical vibrations acting upon a vacuum tube is the relative displacement of the filament with respect to the other electrodes due to the inertia forces. Such displacement changes the internal characteristics of the tube and therefore produce certain variations of current as a function of the relative displacements. In order to understand this feature of my invention, reference is made to Fig. 5 which shows a cross section arrangement of the electrometer tube of my invention in which F_1 , F_2 , F_3 designate the filaments located on the same concentric circle of radius r at an angular distance between each other equal to 120° .

Now suppose that the tube is submitted to an inertia force directed along XX' which will produce therefore minute relative displacement A of all the filaments, parallel to the axis XX' . Each displacement A will modify the electronic current in accordance with the value of its projection on the radius extending from the center of symmetry and going through the original location of the filament.

The value of the modification of the electronic current can be represented by: $dI = AK \cos \alpha$, α being the angle of the displacement with the radius of projection. In my invention the filaments are located at an angle of 120° then the total action of the minute displacements is the vectorial addition of all of them, that is,

$$e_1 = AK \cos \alpha$$

$$e_2 = AK \cos \left(\alpha + \frac{2\pi}{3} \right)$$

$$e_3 = AK \cos \left(\alpha + \frac{4\pi}{3} \right)$$

$$I = e_1 + e_2 + e_3 = AK \left[\cos \alpha + \cos \left(\alpha + \frac{2\pi}{3} \right) + \cos \left(\alpha + \frac{4\pi}{3} \right) \right]$$

but that whatever the value of α is, the following relation exists:

$$\cos \alpha = -2 \cos \left(\alpha + \frac{2\pi}{3} \right) = -2 \cos \left(\alpha + \frac{4\pi}{3} \right)$$

then the total mechanical disturbance of all the filaments so located is:

$$I = e_1 + e_2 + e_3 = AK \times 0 = 0$$

and the conclusion is that as long as the filaments are located around the grid cylinder on a con-

centric circle and with such angular distance from each other that the vectorial sum of their moments in respect with the center is equal to zero, the system cannot be influenced by mechanical vibrations. The conditions of symmetry in respect with a point require that the filaments must number a minimum of three or any multiple of three or any multiple of four. This gives the following possibilities:

10 Number of filaments:

3—4—6—7—8—9—10—11—12—13—14—15

each combination being formed by

15 $N \times 4$ or $N \times 3$ or $(N \times 4 + N^1 \times 3)$

for each of one of these values admit of a center of symmetry, provided that each elementary combination follows the proper angular arrangement.

20 Therefore in the combination of seven filaments, four of them must be at 90° apart while the three others must be at 120° . The conditions of constant electronic density around the grid then admits only the combinations in which the angular spacing may be constant. Like:

3—4—6—8—9—12—15—16—18—20

and so on.

30 The structural arrangement of the electrometer tube is illustrated more clearly in Figs. 6—10, from which it will be seen that the filament and anode elements are arranged within the tube on tripod supports illustrated at F_2 and P_a which project through the envelope of the electrometer tube and 35 provide electrical terminals as well as mechanical supports.

35 The grid G is formed from a thin hollow metallic cylinder such as tantalum. A reduced section forming an annular groove s is provided in 40 one end of the cylinder sleeve by which the glass of the envelope shown at V rigidly supports the grid-like cylinder. An electrical connection G_e is extended from the end of the grid-like cylinder as illustrated in Fig. 6.

45 The material of the bulb may be transparent fused quartz. This material has highly desirable insulating properties for this class of equipment. The bulb is shown at $M—N$ formed in two parts 50 transversely uniting through the circular peripheral contact lips L_1 and L_2 . The peripheral contact lips are fused together during the evaporation process of the tube after assembly of the electrodes within the tube in which the tripod supports F_2 spaced 120 degrees for supporting the

filament electrodes are interposed between the tripod support represented at P_a which serve as mounting means for the plate electrode P .

The filament support includes the tripod members F_2 each of which are formed on substantially a right angle having radially extending portions and normally disposed integrally connected vertically extending portions. The vertically extending portions are welded to the ring member R interconnecting the members F_2 in 120 degrees spaced relation. I provide resilient hook mem-

bers H in welded relation to each of the angularly disposed members F₂ and extending over and within the circular ring member R. The hook members H serve as supports for the upper ends of the filaments F₁, F₂ and F₃.

The lower ends of the filaments F₁, F₂ and F₃ are supported by a tripod member that I have indicated at T having a connecting stem portion which is sealed through the end of the envelope N in a position axially of the envelope as represented at F_c. It will be observed that ring member R has a diameter larger than the diameter of plate electrode P and is spaced away from the end of the plate electrode P and is concentrically related to the grid electrode G.

The peripheral lips L₁ and L₂ meet in face to face contact on opposite sides of the radially extending supports F₂ and P_a which are alternately arranged as represented more particularly in Fig. 8. That is considering the arrangement illustrated in Fig. 8 clockwise the disposition of the supporting means for the filaments and the plate in the same transverse plane and reading in a clockwise direction is F₂ P_a, F₂ P_a, F₂ and P_a. These supporting means are spaced sixty degrees from each other and are electrically insulated through the material of the envelope M—N and are mechanically mounted with very substantial rigidity. Any displacement, however, due to shock vibration tends to produce similar displacement with respect to the filament electrodes and the plate electrode as set forth in Fig. 5 thereby avoiding changes in ion current. The arrangement of the symmetrically disposed filaments spaced at equidistant positions intermediate the grid and plate electrodes serves to decrease the ratio of grid current to plate current and increase the plate current and also increase the ratio of plate current to grid voltage.

For a further understanding of other applications of the principles of the electrometer vacuum tube of my invention reference is made to my copending application Serial Number 569,403, filed December 22, 1944, for Electrometer vacuum tube, said application being a continuation-in-part of the instant application.

While I have described my invention in certain preferred embodiments, I realize that modifications may be made and I desire that it be understood that no limitations upon my invention are intended other than may be imposed by the scope of the appended claims.

What I claim as new and desire to secure by Letters Patent of the United States is as follows:

1. An electron discharge tube comprising an envelope of insulation material, a control element pendently supported axially of said envelope, a filament support comprising a ring member concentrically disposed with respect to said control element, a plurality of supports for said ring member extending radially therefrom and supported at spaced intervals by the wall of said envelope, means carried by said ring member supporting the ends of filament elements, a filament mounting device disposed in one end of said envelope, filament elements mounted between said means and said mounting device, a plate element concentrically disposed with respect to said control element with said filament elements disposed between said control element and said plate element and radially extending members attached to said plate element and projecting into said envelope supporting said

plate element with respect to said filament elements and said control element.

2. An electron discharge tube comprising an envelope of insulation material, a filament support mounted in one end of said envelope, a transversely disposed ring member, means extending through the side walls of said envelope and connected to said ring member and spring arms extending radially inwardly from said ring member and aligned with the filament support in the end of said envelope and filament elements mounted between said spring arms and said filament support.

3. An electron discharge device comprising an envelope of insulation material, a filament support extending through one end of said envelope, a filament support positioned transversely of said tube and supported through the walls thereof, filament elements suspended between each of said filament supports, resilient means carried by the transversely positioned filament support continuously subjecting said filament elements to tension under varying conditions of temperature of the filament elements.

4. An electron discharge tube comprising an insulated envelope, a filament support extending through one end of said envelope, a second support disposed adjacent the opposite end of said envelope, means extending through the side walls of said envelope mounting said second support, a plurality of inwardly directed radially extending resilient hook members carried by said second support, and filament elements supported between said first mentioned filament support and said second filament support, said filament elements being maintainable under tension independently of varying conditions of temperature of said filament elements.

5. An electron discharge device comprising an enclosing vessel, a grid electrode supported axially within said vessel, a cylindrical plate electrode surrounding said grid electrode, a ring-like member concentrically disposed with respect to said plate electrode and disposed in spaced relation with respect to one end of said plate electrode, resilient supports extending radially inward from said ring-like member to equidistant positions intermediate said grid and plate electrodes, filament electrodes carried by said resilient supports and means supporting said ring-like member and said plate electrode through the walls of said enclosing vessel for minimizing relative displacement of said filament and plate electrodes under conditions of vibration.
